UNITED STATES PATENT OFFICE.

WILLIAM RUSSELL, OF MILWAUKEE, WISCONSIN.

RAIL TIE AND FASTENER.

1,321,672.

Specification of Letters Patent. Patented Nov. 11, 1919.

Application filed June 2, 1917. Serial No. 172,496.

To all whom it may concern:

Be it known that I, WILLIAM RUSSELL, a citizen of the United States, residing at Milwaukee, in the county of Milwaukee and State of Wisconsin, have invented certain new and useful Improvements in Rail Ties and Fasteners; and I do hereby declare the following to be a full, clear, and exact description of the invention, such as will enable others skilled in the art to which it appertains to make and use the same.

This invention relates to metallic ties and rail fasteners, and an object of the invention is the provision of a tie formed of a pair of telescoping sections having associated therewith novel forms of rail fastening elements.

Other objects will appear and be better understood from that embodiment of my invention of which the following is a specification, reference being had to the accompanying drawing forming a part thereof, in which:

Figure 1 is a side elevation of a tie constructed in accordance with my invention,

Fig. 2 is a top plan view of the same, showing the manner of supporting companion rails of the tracks thereon,

Fig. 3 is a longitudinal sectional view taken through Fig. 1,

Fig. 4 is a section taken on the line 4—4 of Fig. 2, and

Fig. 5 is a section taken on the line 5—5 of Fig. 1 with the rail removed.

Referring to the drawing in detail, the tie is shown formed of an outer section 1, which is provided with a longitudinally extending groove therein, which opens into the opposite ends of the tie and into the upper side 40 of the tie, and an inner section 2 is slidably received by the groove in the outer section 1 and co-operates with the section 1 in completing the body portion of the tie. The lower portions of the walls of the groove in 45 the outer section 1 are undercut, as shown at 3, and the lower side of the inner section 2 is enlarged, as shown at 4, and has the opposite sides thereof beveled and engaging beneath the undercut portions 3 of the side 50 walls of the groove in the outer section 1. The sections 1 and 2 are provided, at a point intermediate the ends of the tie body, with registering openings which receive the shank of a locking key 5, said key having one 55 end provided with a head 6 that abuts against the adjacent side of the outer section

1 and the opposite end of the key 5 extends beyond the other side of the outer section 1 and is provided with an opening for the reception of a cotter pin 7, which normally 60 holds the key 5 in operative position and prevents longitudinal movement of the inner section 2.

The lower side of the outer section 1 is provided with a relatively wide base flange 8, and the opposite sides of the outer section 1 are provided, at opposite points, with extensions 9, which are formed integral with the sides of the outer section 1 and with the base flange 8 and have their upper ends lying 70 flush with the upper sides of the outer and inner sections 1 and 2. The upper ends of the extensions 9 co-operate with the upper sides of the sections 1 and 2 in supporting the companion rails A of a track, so as to 75 provide a relatively wide supporting surface for the rails. The outer section 1 is provided, adjacent each end, with a pair of rail fastening elements designated, respectively, by the numerals 10 and 11, the 80 fastening elements forming each pair lying, respectively, on opposite sides of the groove in the outer section 1. The rail fastening elements forming the pair 10 lie on the outer side of one of the rails A and have portions 85 engaging over the outer side of the base flange of the adjacent rail, and the fastening elements forming the pair 11 lie on the inner side of the other rail of the track and have portions thereon engaging over the inner 90 side of the base flange of the adjacent rail. The inner section 2 is provided, adjacent the opposite ends thereof, with a pair of rail fastening elements designated, respectively, by the numerals 12 and 13. The fastening 95 elements 12 align with the space between the pair of fastening elements 10 carried by the outer section 1 and are adapted to engage the inner side of the base flange of that rail that is engaged by the fastening element 10, and 100 the fastening element 13 lies on the outer side of the other rail of the track and co-operates with the fastening element 11 in holding the rail in position.

By reason of the fact that the lower side 105 of the inner section 2 is enlarged, as at 4, and which has the opposite sides thereof beveled for engagement beneath the undercut portions 3 of the side walls in the groove in the outer section 1, the sections 1 and 2 110 will be prevented from having relative vertical movement during the passage of rolling

stock over the rails, thereby relieving the locking key 5 from considerable strain.

When the meeting ends of the rails (not shown) meet on top of the improved tie the 5 fish plates (not shown) of the rail joint can be bolted to the extensions 9 and thus the same can be held firmly in place.

It is evident that various changes might be resorted to in the form, construction and 10 arrangement of the several parts without departing from the spirit and scope of the invention as claimed.

Having thus described my invention what I claim as new, is:

15 A tie including a base member having a longitudinally extending channel opening out through one end thereof and terminating

short of the opposite end of the base member, said channel being undercut, a locking section slidably mounted in said channel 20 and having one end abutting the inner end of the channel, rail engaging elements carried by said base member and said locking section, said base member and said locking section being provided with alining openings, and a locking pin extended through 25 said openings.

In testimony whereof I affix my signature in presence of two witnesses.

WILLIAM RUSSELL.
